UNITED STATES PATENT OFFICE.

EUGEN KUZZER, OF DRESDEN, GERMANY, ASSIGNOR TO KLEWE & CO. INCORPORATED, OF NEW HAVEN, CONNECTICUT, A FIRM.

BRUSH FOR CLEANING ARTIFICIAL SETS OF TEETH.

No. 890,148.

Specification of Letters Patent.

Patented June 9, 1908.

Application filed June 5, 1906. Serial No. 320,255.

To all whom it may concern:

Be it known that I, EUGEN KUZZER, physician, a subject of the King of Saxony, and resident of Georgsplatz 2, Dresden, Kingdom 5 of Saxony, German Empire, have invented a new and useful Brush for Cleaning Artificial Sets of Teeth, of which the following is a specification.

This invention relates to a brush for cleaning artificial sets of teeth and consists more particularly in providing a brush at either end of a curved or otherwise shaped handle, the brushes being of different shapes so that the protruding parts of the artificial teeth 10 such as the gum or crowns and the recesses and hidden parts including the clasps and hooks, may be readily cleaned.

Great lack of cleanliness has been noted up to now with regard to artificial teeth on the 20 part of the patients, and even those who did try their utmost to keep the artificial teeth clean failed, as they had no means to help them to thoroughly succeed in cleaning them and saving their remaining real teeth from 25 decaying in those parts where the hooks of the artificial teeth were fixed on to them.

In the accompanying drawings, Figure 1 is a side view of the brush, and Fig. 2 is a section taken in the plane of the line A—B of 30 Fig. 1.

Now I have succeeded in producing a brush which will overcome all difficulties and enable the user to absolutely keep his artificial teeth clean and save his remaining real teeth.

The handle part *a* of the brush has a handy curved shape and is made of any desirable material, preferably celluloid, and it is developed at one end into a plate-like extension. The bristles of the brush *b* at this end 35 of the handle are longer at the rim of the brush as well as at the pointed end of the same than in the middle part of the surface, thus giving the brush the appearance of a hoof and forming a shallow cavity in the active 40 surface of the brush, which cavity tapers off to nothing at the point of the brush. To the other end of the handle there is fixed a spiral brush *c* to pass through the small cavities and more delicate parts of the artificial 45 sets of teeth, such as the hooks and clasps,

the bristles of this spiral brush being so arranged that they become shorter towards the point of the brush and thus also harder and more effective. The larger brush is so shaped and the bristles are of such stiffness that the 55 artificial gum-side and teeth will easily be cleaned by means of the concave shaped surface of the brush, and the cavities and recesses occurring particularly in artificial gum substitute can be kept clean by means of the 60 protruding point of the brush. The spiral shaped pointed brush *c* at the other end of the handle is particularly adapted to easily and thoroughly clean and disinfect the hook-shaped recesses, clasps and hooks, which 65 are all of a more delicate description. The bristles of this latter brush are fixed in a well known manner between two wires, which are wound round each other, the bristles surrounding these wires vertically in a spiral line 70 and the open ends of the wires being covered with a knob, button or the like for safety's sake and also in order to prevent the wire from untwisting. The other ends of the 75 wires are fixed into or onto the end of the handle in any well known manner.

A cleaning brush constructed, formed and arranged according to this invention combines the great advantage of a superb efficiency to clean the artificial teeth, as well as 80 of being exceedingly handy.

What I claim is:

In an article of the character described, a handle, having a flat hoof-shaped brush at one end thereof comprising a plate-like extension of the handle and bristles longer at the rim and outer pointed end of the brush than in the center and rear end thereof, forming a shallow cavity in the active surface of the brush tapering off to nothing at the point of 85 the brush.

In testimony, that I claim the foregoing as my invention, I have signed my name in presence of two witnesses, this 23rd day of May, 1906.

EUGEN KUZZER.
